[57] CLAIM

The ornamental design for the flume platform panel for animal confinement pens, as shown and described.

DESCRIPTION

FIG. 1 is a top perspective view of a flume platform panel for animal confinement pens showing our new design;

FIG. 2 is a side elevational view thereof, the opposite side being the same as the side shown;

FIG. 3 is a bottom perspective view thereof; and

FIG. 4 is an enlarged end elevational view thereof with its center broken away for convenience of illustration, the opposite end being a mirror image of the end shown. The flume platform panel has been broken away in FIGS. 1, 2 and 3 to indicate indeterminate length.
